THEODORE LIVINUS REEPMAKER D'ORVILLE, OF DAYTON, OHIO.

ELECTRICALLY-CONTROLLED COMBUSTION SYSTEM.

1,334,440.

Specification of Letters Patent. Patented Mar. 23, 1920.

Application filed November 26, 1918. Serial No. 264,178.

To all whom it may concern:

Be it known that I, THEODORE LIVINUS REEPMAKER D'ORVILLE, citizen of the United States, residing at Dayton, in the county of 5 Montgomery and State of Ohio, have invented certain new and useful Improvements in Electrically - Controlled Combustion Systems, of which the following is a specification.

10 This invention relates to an electrically controlled combustion system for igniting and burning liquid fuels, wherein a relatively heavy oil is employed as the fuel, and while the system is susceptible of more or 15 less general use for heating purposes such for instance as the heating of intake manifolds of internal combustion engines to facilitate starting in cold winter weather, or the firing of furnaces, it is particularly 20 adapted for use in connection with steam generators.

In the generation of steam as the motive power for self-propelled vehicles such as automobiles, trucks, tractors, launches and the 25 like, it has frequently been the custom to utilize a liquid fuel as the agent of combustion for generating the necessary heat at the burner to vaporize the water. Heavy liquid fuels such as kerosene are generally employed for this purpose and therefore the 30 problem of initially igniting the same and starting the operation of the engine involves the provision of special equipment, more particularly because it is desirable to ignite 35 the burner automatically by an electrical spark. It is a well known fact that a sprayed mixture of kerosene and air, in which a sufficient amount of air is present to insure complete combustion of the mixture 40 cannot be ignited by a small flame such as is ordinarily produced by an electric spark. However, a kerosene mixture having an excess amount of liquid fuel can be ignited by an electric spark.

45 While it has been heretofore proposed to ignite the fuel initially supplied to the burner automatically by an electric spark through the closing of a switch convenient to the driver's seat, the means to this end is 50 nevertheless somewhat complicated and involves much cumbersome equipment, the operation of and attention to which, has been generally regarded as a nuisance by the operator of the vehicle, and in many instances 55 creates a prejudice against the steam driven type of automobiles.

Accordingly, the present invention has primarily in view a novel electrically controlled combustion system, whereby a mixture having an excess amount of kerosene or 60 like fuel may be supplied automatically and similarly ignited by an electric spark through the simple closing of an electric switch which not only performs these two 65 essential functions but also sets in action the necessary associated apparatus for continuing the operation of the burner on a relatively lean mixture.

A further object of the invention is to provide an electrically controlled combustion 70 system of maximum simplicity and which may be relied upon to operate under all conditions of use. That is to say, the present invention aims to eliminate much of the equipment necessary for carrying out a 75 somewhat similar function in devices of this character now in use, such for instance, compressed air involving a hand air pump, motor driven pump, compressed air tank, air pressure gage, various air valves, filter, piping, etc., or else the use of gasoline for priming.

With the above and other objects in view which will more readily appear as the nature of the invention is better understood, 85 the same consists in the novel construction, combination and arrangement of parts hereinafter more fully described, illustrated and claimed.

A preferred and practical embodiment 90 of the invention is shown in the accompanying drawings, in which:

Figure 1 is a diagrammatic view illustrating the relative position of the various instrumentalities utilized in carrying the 95 present invention into effect.

Fig. 2 is a diagram of the electrical arrangement of the system.

Fig. 3 is a vertical sectional view of a portion of the mixer pipe having therein 100 a form of special fuel valve contemplated by the present invention.

Fig. 4 is a diagrammatic view of the centrifugal cut-out which is utilized to break the circuit to the spark plug after the burner 105 has been ignited and also de-energize the solenoid.

Similar reference characters designate corresponding parts throughout the several figures of the drawings.

Owing to the difficulty, heretofore expressed, of igniting a relatively lean mix-

ture of kerosene and air by an electric spark, that is, a mixture with the fuel and air present in such proportions as will avoid soot and clogging up of the operating parts, 5 it is the practice to supply a mixture having an excess of kerosene at the start, and in order to attain this end, so called starting and running nozzles are used, whereby after the mixture has been ignited from the starting 10 nozzle the burner will continue to operate on the lean mixture from the running nozzle only. Obviously, this means of accomplishing the starting not only involves a multiplicity of parts and added equipment 15 but at the same time tends to provide a further source of difficulty in the event of failure of associated parts to operate or properly function. Therefore, the present invention has in view, as previously indicated, a simplified system which involves but one nozzle which performs all of the functions of two nozzles heretofore employed.

With this primary distinction in view, 20 reference may be had to Fig. 1 of the drawings which shows a steam generator S having a combustion chamber 1 at its upper end and an exhaust flue 2 at its lower end, and connected with a radiator or condenser 25 C in any suitable and well known manner which is not important to the present invention. Leading to the combustion chamber 1 is a suitable burner device 3 which consists in the embodiment shown of a relatively short pipe section 4 opening into the combustion chamber at one end and connected at its opposite end with the discharge outlet 5 of a casing surrounding a blower fan driven by a motor 6. On the end of the 30 shaft 7 of the motor opposite the fan is mounted a centrifugal cut-out device designated generally as 8 and diagrammatically shown in Fig. 4 of the drawings. Also, an electric storage battery 9 may be conveniently located with respect to the parts to which it supplies current and an electrical generator 10 is preferably connected with the storage battery through a suitable relay 11 to charge the same in the well known 35 manner. This electrical equipment together with a high-pressure and low-water automatic cut-out 12, a solenoid 13 for controlling the atomized fuel flow from the nozzle, a coil 14 and spark plug 15, completes the 40 electrical equipment of the system.

Referring now to Fig. 3 which more clearly shows the burner device it will be observed that the pipe section 4 carries the spark plug 15 adjacent the combustion 45 chamber end thereof with the sparking points positioned close to and in the path of discharge from a Venturi nozzle 16 suitably supported within the pipe 4, and having an annular fuel supply groove 16^a which 50 cooperates with the support to provide an

annular fuel chamber that communicates with a main fuel supply passage 17. The means for supporting the venturi also serves as a guide for a valve stem 18 whose needle head 18^a is normally prevented from 55 entirely closing fuel escape orifice 20 in the venturi by the flange 18^b resting on the bottom of the socket 18^c. The said stem 18 is also provided with a soft iron core 18^d at its upper end which may be engaged 60 by a spring 19 and lifted through the energization of the solenoid 13 to thereby fully uncover the orifice 20.

In connection with the means for directly controlling the escape of fuel into the venturi that is, the orifice 20 and the head 18^a of the valve stem 18, it is to be observed that when the flange 18^b of the stem rests on the bottom of the socket as above indicated either under its own weight or under tension of the spring 19, sufficient clearance is provided between the conical head and the rim of the orifice so that as the air is forced through the mixing section 4 by the blower, a proper amount of fuel will be 70 sucked out around the head 18^a of the valve to form the proper running mixture. However, upon starting the engine, the ignition of the burner is accomplished through the raising of the valve stem 18 so as to lift 75 the head 18^a, and fully uncover the orifice 20 so that a relatively unobstructed passage for the raw fuel is provided whereby the first blast of air from the fan blower will 80 produce a mixture having a preponderant amount of raw fuel to be blown out of the mouth of the venturi 16 and onto the sparking terminals of the plug 15 which, simultaneously with the starting up of the blower 85 gives off an igniting spark. Thus, it will 90 be apparent that the present burner device 95 contemplates a single nozzle which upon starting is automatically opened to permit a maximum amount of fuel being aspirated 100 through the Venturi nozzle to be ignited, 105 and then, after the burner is in operation, returns to a substantially closed position to 110 permit only a relatively small amount of fuel to escape from the fuel discharge orifice 115 to produce a properly proportioned relatively lean mixture.

For the purpose of the present invention the diagrammatic showing of the centrifugal cut-out in Fig. 8 is sufficient, and from this figure it will be observed that the electric current is conveyed to a suitable metallic portion of the shaft of the device which is co-axial with the blower shaft 7, and thence through the metallic segments 21 which are mounted on the springs 22 fixed 120 at 23 to the rotary disk 24 connected with the motor shaft to revolve therewith, and from thence the current may be conducted in any suitable manner out through the brush or like connection 25. Obviously, when the 125 130

segments 21 are in contact with the metallic portion of the shaft above referred to, current will pass uninterruptedly to the brush 25, whereby as the motor blower increases in speed the rotary element 24 will likewise increase in speed and cause the segments 21 to pull away from the current carrying shaft, and thus interrupt the circuit flowing through the segments and on out 10 through the brush 25.

The entire electrical system may be more clearly understood by reference to Fig. 2 which diagrammatically shows the circuits involved, the apparatus and connections there indicated being the well known Wagner electric system, although it will be understood that my invention is not limited to the use of this system. The storage battery 9 has one terminal grounded as at 9^a while its other 15 terminal is electrically connected by the wire *a* with one terminal of a relay 11, the closing coil of which latter is also grounded, as shown, and whose other terminal is electrically connected by the wire *b* with one 20 terminal of the generator 10. The generator 10 and motor 6 for driving the fan or blower are electrically connected by the wire *c*, and the said motor 6 is connected by the wire *d* with one terminal of the high-pressure and 25 low-water automatic cut-out 12. In connection with the motor 6 it is to be noted that the motor in the Wagner system referred to is grounded via the wire *c* and the series winding of the generator. An electrical connection *e* including a hand switch *f* is connected to the other terminal of the automatic cut-out 12 and with the battery wire *a* as shown. The wire *d* which is connected with the 30 automatic cut-out 12 is tapped by the wire *g* which leads to one of the terminals of the solenoid 13 the other terminal of which is connected by the wire *h* with the metallic shaft of the centrifugal cut-out 8. The current passing from the wire *h* makes its way 35 through the segments 21 of the centrifugal cut-out and thence to the brush 25, from whence it is conducted by the wire *i* to the induction coil 14 and from thence by the wire *j* to the spark plug 15.

50 When the hand switch *f*, which may be placed in any suitable position convenient to the driver, is closed current will flow from the storage battery 9 through the line *c* to the automatic high-pressure and low-water 55 cut-out 12 and from thence to the solenoid 13 for the purpose of lifting the valve head 18^a, and from the solenoid through the wire *h* to the centrifugal cut-out and from thence through the wire *i* to the primary winding 60 of the coil 14 and from thence to the spark plug 15 by wire *j*. Also, when the hand switch is closed and current from the storage battery flows through the line *c* to the centrifugal cut-out 8 and line *d*, the motor of 65 the blower or fan is simultaneously started.

Current will continue to pass through the solenoid 13, centrifugal cut-out 8, coil 14 and spark plug 15 until the blower reaches such a speed as will cause the segments 21 of the centrifugal high-speed cut-out to pull away 70 from the metallic conductor shaft of the cut-out, thus giving ample opportunity for sufficient raw fuel to be supplied to the aspirating venturi 16 to ignite the burner. Obviously, after the burner has been ignited 75 there is no further need of the solenoid holding the valve head 18^a raised, and the speed of the blower which continues to furnish air for the burner will cause the automatic centrifugal cut-out switch to break the circuit 80 to the coil and spark plug.

Accordingly, it will be apparent that when the hand switch *f* is closed three functions take place simultaneously: first the valve stem 18 is lifted through the energization of 85 the solenoid 13 so as to give a rich fuel mixture; second the blower motor is started up to send air through the pipe section 4 and Venturi nozzle 16; and third, current flows through the coil 14 and to the spark plug 90 15 to produce the desired ignition. This entire operation requires but two or three seconds and at the end of approximately that time the centrifugal cut-out 8 comes into operation to interrupt the flow of current to the coil and spark plug. When the current is interrupted to the spark plug the solenoid 13 is of course deenergized and the valve head 18^a falls to its normal position to thus 95 supply only the proper amount of fuel for 100 all running conditions.

With the arrangement described it will also be apparent that if the steam pressure in the boiler reaches an unsafe maximum, or the water falls below the minimum level prescribed for safety, then the combined high pressure and low water automatic cut-out 12 will break the circuit from the battery to the blower motor as well as to the solenoid and spark plug coil box so that all current consumption is immediately stopped. The stopping of the blower motor again cuts in the centrifugal switch; so that when the high pressure and low water switch again cuts in the whole sequence of operation may be repeated. 110 115

From the foregoing it will be apparent that a novel and distinctive feature of the present invention is the provision of means whereby the simple closing of a hand switch 120 operates a single nozzle device so as to supply an initial fuel charge to the spark plug, which fuel charge contains a maximum amount of liquid fuel to insure the preliminary ignition of the burner. Then, after the 125 burner has started to operate, the continued action of the blower which supplies the forced draft to the burner will cause the electrical circuit of the spark plug to be broken automatically and thus prevent the unnecessary 130

sary expenditure of current through this source, and at the same time set the single fuel nozzle automatically to its normal running position. Furthermore, it will also be observed that the burner device discharges into the combustion chamber 1 which is arranged at the top of the generator whereby the heat of combustion must pass downwardly through the flues of the generator 10 to get to the exhaust flue 2. This arrangement produces what may be termed a contrafow generating system since it is proposed to cause the water flow to be opposite to the flow of gases, and has the advantage, among 15 others, of permitting the assembling of the burner device and associated parts in a readily accessible position while at the same time saving long pipe connections and the like which would only complicate the structure and add unnecessary weight.

I claim:

1. An electrically controlled combustion system including a burner device having a fuel nozzle provided with means for automatically varying the quantity of liquid fuel issuing from said nozzle to thereby obtain a relatively rich initial mixture for ignition purposes, and a subsequently relatively lean mixture for continued operation from the same nozzle.
2. An electrically controlled combustion system including a burner device having a fuel nozzle provided with control means for automatically varying the amount of fuel issuing from said nozzle, a spark plug, and means automatically operating simultaneously with the fuel control means to cause said spark plug to ignite the fuel mixture, and subsequently become inoperative.
3. An automatic combustion control system comprising a burner device including a combined starting and running fuel atomizing nozzle, a sparking device, means for supplying an air blast to the burner device, means for releasing a starting charge of fuel, and electrical means for simultaneously causing the operation of the sparking device and air blast means as the fuel atomizing nozzle releases the starting charge of fuel.
4. An automatic combustion control system comprising a burner device including a casing, a combined starting and running fuel atomizing nozzle including a valve arranged within the casing, and including a Venturi tube disposed longitudinally of the casing, a spark plug having its terminals arranged in the path of discharge from the venturi, a blower device for supplying an air blast to the burner casing, and electrical means for simultaneously operating the valve of the nozzle, spark plug, and blower.
5. An automatic combustion control system comprising a burner device including a casing, a combined starting and running fuel atomizing nozzle arranged within the casing,

said nozzle including a Venturi tube within the casing and having a raw fuel discharge outlet therein, a valve including a head adapted to normally restrict the raw fuel outlet whereby a relatively small amount of raw fuel may escape into the venturi, a solenoid for automatically lifting said valve whereby the raw fuel discharge outlet of the nozzle is entirely uncovered, a spark plug having its terminals in the path of discharge from the venturi, a blower device connected with the burner casing, and electrical means for simultaneously energizing the solenoid of the valve and furnishing current to the spark plug, and also causing the operation of the blower.

6. An automatic combustion control system comprising a burner device including a spark plug and a solenoid actuated starting and running valve, a motor operated blower device for furnishing an air blast to the burner device, a source of electric energy, an electrical connection between the said source of electric energy and the blower device and including a switch, another electrical connection between said source of electric energy and the solenoid and spark plug, and an automatic centrifugal high-speed cut-out included in the circuit of the last named electrical connection, said automatic centrifugal cut-out being associated with the blower device to automatically interrupt current to the spark plug and solenoid when the latter reaches a sufficient rate of speed.

7. An automatic combustion control system comprising a burner device including a spark plug and a combined running and starting valve, a motor operated blower device for furnishing an air blast to the burner, electrical means for simultaneously causing the operation of the spark plug and blower device and also setting the fuel valve to starting position, and automatic means associated with the blower device for rendering the spark plug inoperative and permitting the fuel valve to return to its normal position.

8. An automatic combustion control system for steam generators comprising in combination with the generator, a burner device including a spark plug and a combined running and starting fuel supply valve, a blower device for supplying an air blast to the burner, a solenoid associated with the burner device and adapted to cause the fuel valve to discharge a relatively large amount of raw fuel to start the burner and when deenergized permit the fuel valve to return to normal running position, a source of electric energy, an electrical connection between said source of energy and the blower device, said connection including a hand switch and a combined high-pressure and low-water automatic cut-out, an

- automatic centrifugal cut-out associated with the blower and adapted to permit the flow of current therethrough until the blower reaches a predetermined speed, another electrical connection tapping the first mentioned electrical connection between the high-pressure and low-water cut-out and the blower and including in its circuit the solenoid, automatic centrifugal cut-out and the spark plug, whereby when the blower reaches a predetermined speed current will cease to flow in the last mentioned electrical connection, but will continue to flow to the first mentioned connection to continue the operation of the blower.
9. An automatic combustion control system for steam generators, including a generator having a fire box at its upper end and an exhaust flue at its lower end, a burner device opening into the fire box, and including a combined starting and running valve and a spark plug, a blower device for supplying an air blast to the burner, and electrical means for simultaneously supplying current to the terminals of the spark plug and starting the blower and setting the fuel valve to starting position, and automatic electrical means for rendering the spark plug inoperative and returning the fuel valve to running position, but permitting the continued operation of the blower.
10. An electrically controlled combustion system including a burner device provided with a fuel supply nozzle having a discharge orifice, and electrically operated means whereby said orifice may be automatically controlled to discharge fuel for both starting and running purposes.
11. An automatically controlled combustion system including a burner device having a fuel supply orifice, means for automatically varying the outlet area of the orifice to release a relatively large initial fuel charge, and subsequently throttle the orifice to furnish fuel for a lean gaseous mixture.
12. An automatically controlled combustion system including a burner device having a fuel supply orifice, a charge igniting device arranged in operative relation to the burner device, means for energizing the igniting device and simultaneously controlling the fuel supply orifice to provide for a relatively large initial fuel charge and for simultaneously rendering the igniting device inoperative with the reduction of the fuel charge.

In testimony whereof I hereunto affix my signature in the presence of two witnesses.
